UNITED STATES PATENT OFFICE.

CHARLES H. CHAPMAN, OF SHIRLEY, MASSACHUSETTS.

IMPROVEMENT IN LOOMS FOR WEAVING TAPE.

Specification forming part of Letters Patent No. 154,745, dated September 8, 1874; application filed September 29, 1873.

To all whom it may concern:

Be it known that I, CHARLES H. CHAPMAN, of Shirley, in the county of Middlesex and State of Massachusetts, have invented certain new and useful Improvements in Machines for Weaving Tape, of which the following is a specification:

My invention consists in a series of devices for weaving tape, the nature of which can be best understood by reference to the specification and drawings.

Figure 1 is a plan of my machine. Fig. 2 is a vertical section of the same. Fig. 3 is a detail plan showing part of the tape, the weft rod or needle, the shuttle, and their immediate adjuncts. Fig. 4 is an elevation of the parts shown in Fig. 3. Fig. 5 is an elevation showing the device for governing the throw of the harness-frames. Fig. 6 is an elevation showing, in detail, part of the stopping device or stop-motion.

A B represent the frame, to which the other parts of the machine are attached. U, Figs. 1 and 2, is the warp-roller, U² being the warp. This warp passes through the harness-frame N, reeds M³, and over the breast-beam U⁴, then around and between the rolls V, and onto the reel V², Fig. 2. Besides the warp-threads U², I have another warp-thread, E³, Fig. 3, one end of which is connected to the shuttle S, Fig. 3. The other end passes over with the other warp-threads, and is connected to the reel V². The function of the warp or shuttle thread E³ is to form a stitch with the weft-thread E, and thus constitute one of the selvage-edges of the tape, the other selvage-edge being formed by the usual weaving process. The weft-thread E is on the spool E⁴, which is located under the front part of the frame, (see Fig. 1,) from which it passes through the guide-hole E⁵, Fig. 1, to the tension device E¹, Fig. 1; thence through the guides F² and D⁶, Fig. 4, to the spring take-up F, from which it passes back to the eye D⁶ in the heel of the weft-rod D⁴; thence to the hole or eye at D⁵ in the end of the weft-rod, (see Figs. 1 and 4,) from which point it passes to the woven tape. The shuttle S is moved backward and forward by the slide K, operated by the pitman K¹, crank C¹⁰, shaft C⁹, gears C¹ C⁶, shaft C², and driving-pulley C¹. The slide K (see Fig. 3) has a pro-

jecting arm, K², which engages with the rear of the shuttle, and presses it forward; also, an arm, K³, Figs. 2 and 3, having a lever, K⁶, Fig. 2, the lower end of which is held in position by a spring, so as to operate against the front end of the shuttle and cause it to move back. To take the shuttle out of the race, the lever K⁶ can be turned up so as to allow the removal of the shuttle. The weft-rod D⁴ is operated by the pitman D², lever D, and cam C⁹, Fig. 1. The end D⁵ of the weft-rod (see Fig. 4) has an upward projection, as shown, by which the weft-thread is held above the rod at the point where the shuttle passes, so that the point of the shuttle is sure to pass under the thread. Motion is communicated to the reed M³ through the rocker-shaft M¹, Fig. 2, lever M, and cam L on the shaft C², Fig. 2. Motion is communicated to the harness-frames N by means of the connections N¹, N², N³, and R², and levers R¹, and rocking cams R, each frame having a rocking cam, R, to operate it. These rocking cams R are hung on the shaft N⁴, Fig. 2, and are free to oscillate on the same. The shaft N⁴, Figs. 2 and 5, is caused to revolve by a worm-gear, N⁶ N⁵, Fig. 1, which receives motion from the main shaft C², Fig. 1. N¹, Fig. 5, and N⁸ are two cam-wheels, which are fastened to and revolve with the shaft N⁴, Fig. 4. P is a rocking frame, swinging about the shaft N⁴, to which motion is communicated by the arm P¹, operated by the cam P⁴ on the shaft C², so that, when the lever is in motion, P is constantly vibrating back and forth. P² is a pawl attached to P, and arranged to operate the rocking cam R, so that as P vibrates it will throw the cam forward, thereby lifting the arm R¹, and, through R² N³, giving motion to the harness-frame. The pawl P² has a small pin, P³, projecting from it, and extending over the periphery of the cam N¹, and, as the cam N⁷ revolves, the high parts of the same will come in contact with the pin P³, and lift the pawl P² up, so that it will not come in contact with the notch in the cam R, and, consequently, the harness-frame to which it belongs will remain stationary. The frame Q, pawl Q¹, pin Q², and cam N⁸ are arranged to operate on another rocking cam, similar to R, for the purpose of operating another harness-frame or sets of frames. The

number of these devices for operating the harness-frames will depend upon the character of the work to be produced. The belt-shippering device shown in Figs. 1 and 2 consists of a belt-fork spring-lever, T^8 , and vertical rod T^7 , which is bent at its upper end, so as to form a handle, T^6 , as shown in Figs. 1 and 6; and upon the shaft T^7 I fix a holding-lever, T^9 , which is caught by a latch, T^4 , Fig. 1. This device is to prevent the belt-shipper from springing back and throwing the belt onto the loose pulley C.

When the loom is in motion, and it is desirable to throw the belt off, and thus stop the loom, it is only necessary to push the latch T^4 out of contact with the lever T^9 , in which case the shipper will fly back, and the machine stop.

In Figs. 1, 2, and 6, I show an automatic device for throwing off the latch T^4 , and thus stopping the loom, when, from any cause, the filling-thread is not woven into the warp. This device consists of a lever, T, (see Fig. 2,) the upper end of which rests upon the woven tape. Immediately under the point of the feeler-lever T a hole is made in the breast-beam, which is covered by the tape, the tape preventing the point of the lever from going into the hole, which it would otherwise do, being impelled by the spring t. Now, if the warp is unfilled, and the machine continues to run, the warp-threads alone will not be suffi-

cient to prevent the point of the feeler-lever T from falling into the hole in the breast-beam. When this takes place, the opposite end T^1 of the lever rises up, taking with it the bent lever $T^2 T^3$, Fig. 6. This bent lever $T^2 T^3$ is fastened to the rear of the latch T^4 , Figs. 1 and 6. If this bent lever $T^2 T^3$ is moved by the action of the feeler-lever T T^1 , so as to come opposite the rod K^5 , (see Figs. 3 and 6,) then, as the shuttle-carrier K advances, K^5 (see Figs. 3 and 6) will hit the lever T^3 , Figs. 3 and 6, and push it outward, carrying with it the latch T^4 , and thus releasing the shipper-holder T^9 , and stopping the loom.

The thread-guide F^2 and take-up F, Fig. 4, are attached to the weft-rod D^4 , Fig. 1, so that they move with it, and thus greatly lessen the sudden tension on the thread.

I claim as my invention—

1. The combination of the feeler-lever T, the bent lever $T^2 T^3$, and latch T^4 with the rod K^5 , all operating substantially as described, and for the purpose set forth.
2. The combination of the cams $N^7 N^8$ and the rocking cams R with the lever P Q and pawls $P^2 Q^2$, all operating substantially as described, and for the purpose set forth.

CHARLES H. CHAPMAN.
